UNITED STATES PATENT OFFICE.

ALFRED T. HEYMANN, OF HAMBURG, GERMANY.

EXTENSION TABLE.

Application filed August 26, 1921. Serial No. 495,536.

To all whom it may concern:

Be it known that I, ALFRED T. HEYMANN, a citizen of Germany, residing at Hamburg, Germany, have invented certain new and useful Improvements in Extension Tables (for which I have filed an application in Germany, January 19, 1919), of which the following is a specification.

My invention relates to extension tables and more especially to extension tables of circular or oval form. Circular extension tables are old which have underneath the normal leaf of the table extension boards which, after the table has been extended, are turned upward so as to be within the plan of the table leaf. These old tables are as a rule so formed, that at least the lateral edges of the extended table are parallel to the slides.

It is an object of my invention to provide an extension table of circular or oval form which is oval when extended, whereby the advantage is obtained that all the persons sitting round the tables can see one another without bending forward.

Extension tables of circular or oval form are old, which when extended are also oval. In these tables, however, loose boards must be inserted after the table has been extended and the central portion of the table which is removed must be stored away separately.

Now, the object of my invention is not only, as mentioned above, to keep the extension boards below the table boards and bring them into the plane of the table board by turning upwards, but I desire also to discard the normal central portion of the table, which, if the table is to fulfill its purpose, can only be done by concealing this normal central portion of the table leaf mechanically within the table.

According to my invention, not only, as is known the extension boards, but also the normal central portion of the table leaf are so arranged, that they may be folded into the table and brought into the plane of the table leaf respectively.

It is however, to be considered, that on the one hand, as my invention relates to tables of circular or oval form, less space is available for the arrangement of the exten-

sion plates, than with the ordinary tables the longitudinal edges of which are parallel to the slides. In particular, as the outer slides are comparatively very short and the extensions must overlap approximately for the same amount as in long extensions, a greater number of extensions is necessary which further limits the free distance between the slides.

On the other hand, it is to be considered, that if it is desired to convert a small circular or oval table into a large oval table, the extensions must not only have curved edges, but also greater dimensions in the transverse direction of the table, than in extension tables having parallel lateral edges.

The solution of the problem is, therefore connected with particular difficulties. These difficulties are overcome according to my invention in the following manner: Not only the extension boards, but also the central portions of the table leaf which can be dispensed with after the extension has been effected are hinged to the table so that, when the table is extended, the original central portions of the table leaf are folded into the table and the larger extension plates are folded into the place of the table leaves so as to form a larger table which is also oval.

The table according to my invention can be constructed in two ways. It is possible either to arrange the normal central portion of the table leaf and the larger extension plates on a common hinge, so that the two kinds of plates can be turned round simultaneously and one kind is concealed in the table, when the other kind is used or the arrangement may be such, that the normal central portion of the table board and the extension leaves are adapted to be folded by turning about separate hinges which are arranged in separate horizontal planes. In this case, however, the normal central portions of the table can only be folded into the table after the table has been extended so far that the portions referred to lie sideways of the extension plates. If now the extension plates are turned into the plane of the table leaf, the table may again be pushed together so far that the desired extended oval table is

formed, the normal central portion of the table board being disposed underneath the extension leaves.

In the drawings affixed to this specification and forming part thereof, two modifications of a table embodying my invention are illustrated diagrammatically by way of example. In the drawings—

Fig. 1 is a plan view of a table of circular form, which by means of an extension plate can be converted into a larger table of oval form,

Fig. 2 is a section on line A—A of Fig. 1.

Fig. 3 is a plan view of the extended oval table,

Fig. 4 is a section on line B—B of Fig. 3.

Fig. 5 is a plan view of a circular table which by means of two extensions can be converted into a larger oval table,

Fig. 6 is a section on line C—C of Fig. 5.

Fig. 7 shows the extended oval table and

Fig. 8 is a section on line D—D of Fig. 7.

Referring to the drawings, the table illustrated in Fig. 1 is of circular form, but it may as well be oval without departing from my invention. 1 is the frame and 2 are the legs of the table. The leaf of the table is, in the normal as well as in extended condition, formed of three portions, the end portions 3 and 4 and the central portion 5. The end portions 3 and 4 are connected with one another by the normal slides 6, so that the end portions 3 and 4 can be drawn apart as usual in extension tables. In the example illustrated, the legs 2 and the frame 1 remain stationary. The central portion 5 is also composed of two or, as illustrated, three sections, which are connected by hinges. *a* and *b* are the outer sections, while *c* is the central section. Both outer sections can be folded, as illustrated by dotted lines in Fig. 2, and maintained in this position by means of a bolt 7. One of the sections forming the central insertion 5, here section *c*, is pivoted on an axle 8 arranged in the diameter of the table, preferably by hinges 9, so that, when the sections *a*, *b* and *c* are folded as illustrated in Fig. 2, the central portion 5 can be turned about axle 8. The ends of the axle 8 are, in the example illustrated, secured in the frame.

If it be desired to convert this circular table into a larger oval table, the central portion 5 will be too small, so that a larger central portion must be substituted for it. For this purpose an insertion 10 is arranged below the table leaf which, in the example shown, also consists of three sections, a central section *d* and the two end sections *e* and *f*. This insertion is not only longer, but also wider than the normal insertion 5. It is preferably of such dimensions as to find room in the frame 1, (Fig. 1). The sections *d*, *e* and *f* of this insertion 10 are connected with one another by hinges and

the outer edges of the end sections *e* and *f* are such form that after they have been extended, the table is oval and formed to a continuous curve, so that all persons sitting round the table may see each other without bending forward. As the insertion 10 is of greater dimensions than the normal insertions, the end sections *e* and *f*, when folded, overlap and are held by a bolt 11.

The insertion 10 is also hinged to the axle 8 at the centre of the table, preferably by means of hinges 12, so that it can be rotated about axle 8. As the two insertions 5 and 10 are placed over one another, one of them must take part in the rotation of the other, that is, if one is concealed, the other will appear.

By means of this construction the circular table illustrated in Fig. 1 can be converted into the larger oval table indicated by dotted lines in Fig. 3. This is simply effected by folding the end sections *a* and *b* of the smaller insertion 5 onto their central section *c*, whereupon the end sections 3 and 4 of the plate are drawn apart, which is effected by means of the slides in the usual manner, whereupon the folded insertion 5 is turned on the axle 8, whereby the smaller insertion 5 is concealed in the table while the larger insertion 10 appears and may be brought into the plane of the table leaf by unfolding sections *e* and *f*. The smaller insertion 5 is now disposed underneath the table leaf. Preferably that portion which is under the table leaf, is maintained in its position, so that it cannot move farther.

In the second modification of my invention illustrated in Figs. 5—8, the same principle is applied, but to a table whose frame is also divided so that it is displaced together with the table legs, when the table is extended. At the same time, a greater extension of the table is desired here and consequently two insertions are provided.

As appears from Fig. 5, the table is circular, but it might also be oval without departing from my invention. In proportion to the greater extension of the table, the number of slides 6 has been increased. The central portion intermediate the two end portions 3 and 4 of the table is divided into two sections 5' and 5''. Each section of this central portion is again divided in the middle, so that the section 5' is formed of two halves *g* and *h* and section 5'' of two halves *i* and *k*. Instead of an axle which passes right through the table, the two insertions 5' and 5'' are arranged on two separate axles 14 and 15, which are not disposed in the centre of the table, but laterally to it, and carried in the end portions 3 and 4, respectively. When these central insertions are folded, each of the two halves 5' and 5'' is folded, section *h* being folded on section *g* and section *k* on section *i*. When these cen-

tral insertions are free to be unfolded, which, as will be shown, is only possible after the table has been extended, the insertion 5' will turn about the axle 14 and the insertion 5" about the axle 15, so that both sections of the insertions take up the position illustrated in Fig. 7, in which, when unfolded, they are supported by holders 16 and 16', respectively, which are arranged at the end portions 3 and 4 adapted to be drawn apart.

When the table has its normal form, two insertions 17 and 18, respectively, are disposed underneath the table leaf. Each of these insertions again consists of two halves, *l*, *m* and *n*, *o*, respectively, which are hinged to one another. These insertions turn on pins 19, 19' and 20, 20', respectively, which are carried by arms 21, 21' and 22, 22', respectively. The arms 21, 21' are secured to the same slide, for instance 6', and the arms 22, 22', to another slide, for instance 6", preferably in such a manner, that, on the table being extended, one of the extension plates moves to one side and the other to the other. The pins 19 and 20 extend in different horizontal lines, so that, as will best be seen from Fig. 6, the two extension plates are disposed below one another and below the table leaf at the normal condition of the table. They are supported in this position by holders 23, 24.

If this table is to be extended by drawing apart the end portions 3 and 4, it must at first be extended until the insertions 5' and 5", respectively, which are on top in their normal position, stand beside the extension plates 17 and 18, respectively. It follows, that the table must at first be extended as far as the position illustrated in Fig. 7. In the modification illustrated, the frame and legs will also be displaced during this extension. It may be mentioned here, that, when the end portions are farthest apart, loose insertions might be placed between these portions. In this manner, a table will be formed having straight and parallel lateral edges and two semi-circular ends.

The principal object of my invention, however, is, to provide a table which is of oval form also when extended, so that it forms a continuous curve and the persons sitting round the table can see one another without bending forward. If now, as mentioned, the table is extended so far, that the normal insertions 5' and 5", respectively, stand beside the extension plates 17, 18, all plates may now be unfolded or may be turned on their hinges, first the normal insertions 5 and 5', which must be concealed underneath the table leaf. The extension plate 17 is brought into the plane of the table leaf by turning it about the axles 19, whereupon the two sections *l* and *m* are unfolded and the extension plate is in a posi-

tion to be used. In the same manner, the extension plate 18 can now be turned upward about pins 20, 20'. If now, after the extension plates are in position, the two end portions 3 and 4 are pushed together, first 70 the straight edge of these end portions will engage the straight edges of the extension plates 17 and 18, so that the table has the oval form indicated at the centre of Fig. 7. During this pushing together, the insertions 75 5' and 5", which had previously been folded into the table, will be moved below the table leaf formed by the extension plates 17 and 18.

Obviously, there might be a greater number of extension insertions, if a further extension of the table is desired.

The principle illustrated in Figs. 5-6, where the axles for the smaller central insertions and for the extension plates are 85 separate, may also be employed in the tables with only a single extension plate, as illustrated in Figs. 1-4.

I claim:

1. An extension table of substantially 90 curved peripheral configuration comprising in combination, a pair of end leaves, pairs of slides underneath said leaves and a foldable middle leaf and a foldable insertion leaf, one on top of the other hingedly attached between and rockable about an axis extending in parallel to said slides, the unfolded insertion leaf being of greater length and width than the unfolded middle leaf. 95

2. An extension table of substantially 100 curved peripheral configuration comprising in combination, a pair of end leaves, pairs of slides underneath said leaves, and a foldable middle leaf and a foldable insertion leaf with curved lateral edges, one on top of the other, rockable about axes extending in parallel to said slides, the unfolded insertion leaf being of greater length and width than the unfolded middle leaf. 105

3. An extension table of substantially 110 curved peripheral configuration comprising in combination, a pair of end leaves, pairs of slides underneath said leaves, and a foldable middle leaf and a foldable insertion leaf with curved lateral edges, one on top of the other, hingedly attached between and rockable about axes extending in parallel to said slides, the unfolded insertion leaf being of greater length and width than the unfolded middle leaf. 115

4. An extension table of substantially 125 curved peripheral configuration comprising in combination, a pair of end leaves, slides extending underneath said end leaves, a pair of middle and a pair of insertion leaves, with curved lateral edges, said middle and said insertion leaves being foldable about axes extending in parallel to said slides, said middle leaves being hingedly attached to said end leaves, said insertion leaves being 130

hingedly attached to said slides and being broader than said middle leaves.

5. An extension table of substantially curved peripheral configuration comprising in combination, a pair of end leaves, slides extending underneath said end leaves, a pair of middle and a pair of insertion leaves with curved lateral edges, disposed in differ-

ent planes and foldable about axes extending in parallel to said slides, said middle leaves being hingedly attached to said end leaves, while said insertion leaves are hingedly attached to said slides and are broader than said middle leaves.

In testimony whereof I affix my signature.

ALFRED T. HEYMANN.
